Primary Examiner — Natasha Vujcic*Assistant Examiner* — Gilbert B Ford(74) *Attorney, Agent, or Firm* — Tsz Lung Yeung(57) **CLAIM**

The ornamental design for a compression sock, as shown and described.

DESCRIPTION

FIG. 1 is a perspective view of a compression sock in an in-use configuration for right leg, showing my new design; FIG. 2 is a front view thereof;

FIG. 3 is a rear view thereof;

FIG. 4 is a right side view thereof;

FIG. 5 is a left side view thereof; and,

FIG. 6 is a bottom view thereof.

The broken lines depict portions of the compression sock that form no part of the claimed design.

1 Claim, 6 Drawing Sheets(56)
